PROGRAM CLOCK

Leon Y. Lassiter, Columbia, Mo.

Application October 13, 1944, Serial No. 558,573

3 Claims. (Cl. 161—2)

1

This invention relates to improvements in program clocks for use in schools, factories and such places where it is desired to have signals sounded or given at regular and predetermined intervals.

The primary object of the invention is to provide an apparatus of this nature which is simple, efficient and positive in operation and which has a wide range of adjustment such that it may be set up to give signals at intervals of as little as one minute, and on any selected days of the week.

Another object is to provide in such an apparatus simple and effective means for controlling the duration of the signals.

A further object is to provide for the complete and flexible control of all operations of the clock, including means for disabling the signal circuits without disturbing their settings and without stopping the driving mechanism, and means for manually sounding the signals independently of the time settings for the automatic operation thereof.

Still another object is to provide a convenient and attractive cabinet or housing in which the program clock and associated mechanism may be concealed but in such manner as to provide for convenient access thereto for adjustments, and with a time or regular clock exposed to view and synchronized with the program clock. The housing also provides exposed switches for sounding the signals manually.

Still a further object is to provide a program clock structure embodying as its driving motor a synchronous electric clock unit permitting the program of signals to be accurately synchronized with the regular electric clocks of the school or other location in which the mechanism is installed.

Other and ancillary objects of the invention will be made apparent in the course of the following detailed specification, reference being had therein to the accompanying drawings wherein:

Figure 1 is a frontal elevation of the program clock, showing the same as built on a panel forming a part of the rear section of the cabinet or housing.

Figure 2 is an enlarged detail view of a fragment of the program chain used in my structure.

Figure 3 is a frontal elevation of the housing showing the time clock disposed in the front sec-

2

tion thereof, and showing the program clock panel partially broken out to disclose parts of the program clock mounted behind the same.

Figure 4 is a side or edge view of the housing with an upper part of the rear wall broken out to disclose the interior mechanism.

Figure 5 is a side view of a lower part of the housing and the tubular shield for the program chain, with parts broken away to show interior arrangements.

Figure 6 is a view similar to Figure 1 but showing a modification of the clock structure using a shorter chain and adapted to give signals at intervals of five minutes, or multiples thereof.

Figure 7 is a fragmentary rear elevation of the panel of the clock of Figure 6 and of parts of the mechanism mounted thereon.

Figure 8 is a wiring diagram of the program clock and associated elements.

Referring now more particularly and by reference characters to the drawings, my program clock apparatus, as shown in Figures 1 through 5, is built in a cabinet or housing having a rear section 10 adapted to be secured to a wall 11, or other support, and a front section 12 hinged to the rear as at 13 and with a clasp and lock device 14 for holding said front section closed over and against the rear. Both sections have substantial depth defined by walls and upper and lower ends as clearly shown, and the open front of the rear section is closed by a panel or mounting plate 15 releasably secured in place by the screws 16. This panel 15 supports practically all of the parts of the program clock, as will now be described, and makes installation of the apparatus in any type of cabinet very convenient.

The driving motor for the clock is a synchronous electric unit 17 secured by its base 18 to the rear of the panel 15 and arranged with its hour hand spindle 19, minute hand spindle 20, and sweep second hand shaft 21 extending through the panel to the front thereof. A dial 22 is provided on the front of the panel centered about the axes of these shafts to facilitate the proper setting of the mechanism and a sweep second hand 23 is provided at the extremity of the shaft 21 to make such settings accurate.

As here shown two driving sprockets 24 and 25 are secured, one in front of the other, on the minute hand spindle 20 and each has sixty teeth

around its periphery adapted to engage a linked program chain trained thereover. One of such chains is herein shown and designated at 26, and both are duplicates insofar as their construction and arrangement is concerned. Each chain has seven hundred and twenty links, corresponding to the number of minutes in a twelve hour period, and they are accordingly of considerable length. To accommodate this length I provide near the lower edge of the panel 15 a spaced pair of double grooved, flanged pulleys 27-28 journaled upon pins 29 and the chains, hanging from the driving sprockets, are passed down over inner sides of these pulleys and, thus having their side portions brought into proximity, they drop into the open upper end of a tubular shield member 30 (Figure 5) which extends into the housing in the proper position for this purpose. The shield member is supported at its upper ends by screws 31 in a bracket 32 which is secured as shown to the lower end of the housing section 10 and which has a flange 32a secured to the wall 11 to support the housing therefrom. The lower end of the shield member 30 is received in the eye 33 of a screw 34 fastened in the wall and holds the shield perfectly vertical. Two idler sprockets 35-36 are disposed near the lower end of the shield member and the lower eight portions of the chains are trained thereover (Figure 5), and the chains are thus seen to be wholly enclosed while being free to advance as the driving sprockets 24-25 rotate. The idler sprockets 35-36 are carried upon a base plate 37 secured by a screw 38 to the inner side of the shield member and the base plate has a slot 39 through which this screw passes in such manner as to permit up and down adjustments of the idlers in order to keep the chains taut. A section 40 of the shield member is removable as clearly shown to permit access to the idlers and to this screw 38. A portion of the other program chain appears at 26a in Figure 5.

Arranged over each driving sprocket 24 and 25, and in the same vertical plane, are two separate circuit control switches designated generally at 41 and 42 and each of which is of the normally open leaf spring type, one switch having a lower contact leaf 43 and upper contact leaf 44 while the other has corresponding lower and upper leaves 45 and 46 of similar form. These leaves of the switches are mounted upon the bracket 47 secured to the face of the panel and all are insulated from each other, and from the bracket, by conventionally arranged insulation represented generally at 48. Disposed beneath the lower leaves 43-45 of the switches are wear strips or spring leaves 49 which have cam blocks 50 on their undersides adapted normally to just clear the program chains where they pass over the driving sprockets. An insulating bushing 51 in the panel 15 immediately at the ends of the switches permit the leads therefrom to be carried back behind the panel as clearly shown.

For cooperation with the circuit control switches 41-42, I provide the program chains with signal clips, best shown in Figure 2, designated generally at 52 which take the form of extra links like those used in the chains themselves which extra links, when slightly spread, may be clipped over any one of the links and will then tightly engage the same to stay in place on the chains. These clips 52 will then project, as represented at 53, beyond the outer surface of the chains and hence will, as they reach the said switches, engage the cam blocks 50 to urge the lower switch leaves 43, or 45, upwardly into con-

tact with the upper leaves 44, or 46, thus closing the switches. Every link of the chains may be used to support the signal clips, instead of every other link as in prior devices, thus reducing the necessary length of the chains by one half.

Obviously the driving sprockets 24-25 will make one complete revolution per hour and, having sixty teeth, will accordingly advance the chains a distance equal to one link each minute. 10 This being true it follows that the positions of the signal clips 52 on the various links of the chains will control the times at which the switches 41-42 will be closed, it being possible to close these switches at intervals of as little as one 15 minute apart, or at longer intervals which are multiples of one minute. Thus if it is desired to give signals at fifteen minute intervals the clips 52 will be disposed on every fifteenth link and the sequence of signals will keep up for twelve hours 20 and be then repeated. The intervals between signals may, of course, vary as required and to facilitate counting off the links from the starting point, in setting up the program initially, the links corresponding to fifteen minute intervals 25 (or other arbitrary number) may be distinctively colored, as represented by the black links 54, to stand out from the rest of the chain.

Inasmuch as in most installations signals will be required only during one twelve hour period 30 of the day, as for example from six in the morning until six in the evening, and only on certain days of the week, I provide what I term a calendar switch mechanism for disabling the signal circuits for preselected periods.

35 This switch mechanism comprises a shaft 55 journaled through the panel 15 below the dial 22, or in any other selected location, and which shaft at the front of the panel carries a toothed disk 56 cooperating with a finger 57 secured to 40 and extending radially from the hour hand spindle 19. Each time this finger passes the calendar switch mechanism it will engage one tooth of the disk 56 and advance the same a certain increment, with one such advance movement occurring once each twelve hours. In the arrangement shown, this movement of the disk, and its shaft 55, takes place at six hours on the clock dial, both ante and post meridian.

Mounted on the shaft 55 behind the panel 15 50 is a cam disk 58 and the calendar switch itself, represented at 59, has the normally open contact leaves 60 and 61, one of which coacts with a spring 62 having a V-shaped tooth 63 adapted to ride the periphery of this disk. The switch leaves are supported by a bracket 64 and insulated in usual manner. So long as the tooth 63 rides the edge of the cam disk the leaves 60-61 are pressed into contact (Figure 3) but the disk has a series of notches 65 in its edge 60 into which the tooth may drop in sequence as the disk rotates, and each time this occurs the spring 62 will permit the switch leaves to spring apart to open the switch at such time.

By proper spacing and location of the notches 65 according to the distance the disk moves each time, it will be apparent that the switch 59 may be caused to stand closed for any twelve hour period and open for any other, and may be caused to open during the night hours when signals are not ordinarily required. Also by properly positioning the notches 65 so that the switch will be opened for several sequential positions of the disk 58, as shown at 65a, the circuits (later to be described) may be disabled for full twenty-four 75 hour periods of selected days.

As herein shown the calendar switch mechanism is arranged to disable the signal circuits one half of each day of the week except Saturday and Sunday, on which days the circuits are idle for full twenty-four hour periods. To indicate the condition of the calendar switch and facilitate setting it up initially, I provide a dial 66 on the frontal end of the shaft 55 and the surface thereof is evenly divided into seven spaces marked with the days of the week and doubly divided to indicate the twelve hour periods of each of the days on which appear the words "Off" and "On" indicating the corresponding conditions of the switch. Note that "Off" occurs twice opposite the sections marked Saturday and Sunday. This set up is suitable for school use but the mechanism may be readily changed for other uses requiring different operating periods by simply changing the disk 58 and dial 66 with others appropriately notched and marked. A pointer 66a is provided for the dial.

To prevent the driving sprockets 24-25 and other parts from overrunning and to stop the parts in proper positions each time, I provide a click spring 67 secured to a bracket 68 on the panel 15 and engaging one of the sprockets in a well known manner. A similar spring 69 secured to a bracket 70 engages the toothed disk 56 for a similar purpose.

Disposed behind the panel 15 is a signal switch, or interrupter, designated generally at 71, again of the normally open leaf contact type having contact leaves 72 and 73 suitably insulated and supported on a bracket 74 secured to the panel. A wear strip 75 is provided and the free ends of these parts extend adjacent to the second hand shaft 21 for actuation by an arm member 76 secured thereto. This arm member 76 extends radially from the shaft and has a finger 77 at its extremity which will engage the wear strip 75 and press the contact leaf 72 toward leaf 73 once each minute. An elongated end 78 of this switch leaf 73 is engaged by a cam 79 of insulating material which is carried on a shaft 80 journaled through the panel. By adjusting this off center cam 79 the switch contact leaf 73 may be moved toward or away from the other leaf 72 and thus the part of each minute during which the finger 77 will hold the leaves together will be varied. Thus the duration of each closed period of the switch may be varied and controlled within wide limits and the function of such control will presently appear.

The shaft 80 forwardly of the panel has a pointer 81 playing over a scale 82 on the panel and this pointer may be readily adjusted by hand to move the cam and control the switch as described.

A conventional synchronous electric clock 83 is mounted in the front wall 84 of the cabinet or housing and is exposed to view when the front section 12 thereof is closed. Also mounted in this front wall 84 are two conventional push button switches 85 and 86 which, as will presently appear, bridge the signal circuits in such manner as to permit the signals to be given manually at any time. On the panel 15 I mount a master switch 87 which is connected to control the entire signal mechanism and two separate snap switches 88 and 89 for individually disabling the separate signal circuits without halting the operation of the driving motor 17. The various connections to exterior parts and supply lines are brought out through a conventional outlet box 90 on the upper end of the cabinet.

Referring now to Figure 8 particularly the wiring of the foregoing parts will be described. Two distinct signal circuits are shown, although more or less of such circuits may be employed by providing an appropriate number of program chains. One circuit has a signal 91 and the other a signal 92 which at a common point are connected to a battery 93 or other suitable source of operating potential, the necessary three leads 94, 95 and 96 then leading to a terminal block 97 disposed in the outlet box 90 previously described. From this terminal block 97 the common lead 98 for both circuits leads to the push button switches 85 and 86 and the wires 99 and 100 from the separate signals lead to the other terminals of these switches. Obviously then by pressing either push button switch 85 or 86 the corresponding switches may be actuated at any time and independently of the time control.

Also from the common lead 98 a wire 101 leads to one terminal of the signal switch 71 and the other terminal of this switch is in turn connected by wire 102 to one terminal of the calendar switch 59. The other terminal of this switch is then connected by wires 103 to one terminal of each circuit control switch 41 and 42. The other terminals of these switches are separately connected by leads 104 and 105 to the switches 88 and 89 respectively which are in turn connected thence by wires 106 and 107 to the signal circuit leads 99 and 100. The switches 59 and 71 are thus seen to be series connected with both circuit control switches 41 and 42 and to complete either signal circuit requires the closing of three distinct switches.

The supply for the driving motor 17 is connected to a terminal block 108 and thence to the terminal unit 109 of the motor by wires 110 and 111. The master switch 87 is in one side of this supply circuit so that the motor may be stopped at any time. The clock 83 is connected across a terminal block 112 which is connected by wires 113 and 114 to the supply terminals at 108 and in such manner that the master switch 87 will have no control over the clock.

A tap lead 115 is connected to the controlled side of the signal switch 71 and to a terminal point 116 for conveniently connecting another program clock into the circuits and controlling the signals thereby. Such clocks of the single action magnetic type which advance one minute each time they are energized would be connected in parallel between the terminal point 116 and the common connection between the signals 91-92 as will be understood.

It is believed that the operation will be understood from the foregoing without extended description at this point. Obviously the driving motor 17 and electric clock 83 will operate in accurate synchronism, without mechanical connections of any kind, and the signal clips 52 being properly placed on the program chains will cause the signals to be sounded exactly at the desired and predetermined times. The sweep second hand 23 facilitates the initial synchronization of the program clock with the clock 83 and, once the driving sprockets and program chains are properly arranged to bring one of the signal clips under the circuit control switches 41-42 exactly on the minute, accuracy of all signal intervals will be insured.

Inasmuch as the calendar switch 59 and signal switch 71 are series connected with each other, and the circuit control switches 41-42, both switches 59-71 must be closed before the closing

of switches 41—42 will complete the signal circuits. This being true the circuits will not be activated unless the calendar switch mechanism is in proper condition and the opening and closing of the signal switch, being controlled in duration by the cam 79, will have absolute control over the duration of each signal sounded by the program clock.

Convenient access to the program clock mechanism may be had for setting up the program chains and making other adjustments by opening the front section 12 of the cabinet, but this section may be locked to prevent such access being obtained by unauthorized persons.

Attention is directed to the important fact that the action of the mechanism is intermittent and that it remains stationary except for a period of approximately three seconds of each minute. For this purpose the eight toothed gear 76a is provided and the arm member 76 engages this gear once each minute, advancing the gear one tooth each time it is engaged. Such movement is exactly equal to one minute travel of the minute sprocket 24. The member 76 engages the gear 76a just one-half revolution after it closes the signalling point blades 72—73 and provides one-half minute synchronization between the advancing action and the signalling action.

Referring now more particularly to Figures 6 and 7 of the drawings, I have shown therein a modification of my program clock wherein the signals will be given ordinarily at five minute intervals or multiples thereof. The panel, driving motor and calendar switch mechanism in this clock are exactly as previously described and are, accordingly, indicated by the same reference characters. Only one driving sprocket is required and is indicated at 25 and in distinction to the previous structure this sprocket has twelve studs 117 on its forward surface evenly spaced therearound and corresponding, therefore, to five minute intervals of time. These studs 117 co-operate with a twelve toothed sprocket or ratchet disk 118 which is carried on a shaft 119 journaled in a bracket 120 on the panel 15, the studs advancing the sprocket one tooth every five minutes as will be clearly apparent.

The shaft 119 carries one (or more according to the number of signal programs desired) driving sprocket 121 over which is trained the program chain 122 carrying the signal clips exactly as has been described. This chain being advanced one link every five minutes has only one hundred and forty-four links and is accordingly much shorter than the chains of Figures 1 to 6. It may in fact be wholly contained within the cabinet and runs over two idler sprockets 123 and 124 journaled on the front of the panel adjacent the lower corners thereof. The tubular shield member is not required and the installation is somewhat more compact as a result.

The sprocket 119 is engaged by a click spring 125 secured to the panel at 126 to prevent it from overrunning.

In this structure the signal switch, indicated generally at 121, has the two contact leaves 123 and 125 supported on the bracket 130 secured to the back of the panel 15 and a wear spring 131 moves the lower leaf 125 to close the switch. This movement is brought about by means of a lug 132 carried by and radially projecting from a toothed disk 133 which disk is rotated by a suitable geared connection 134 with a part of the gear train of the driving motor mechanism to make one complete revolution every five min-

utes. Thus once each five minutes the lug 132 will engage the hump 135 on the wear spring 131 and close the switch, such five minute intervals corresponding with the intervals at which the program chain closes the circuit switch 42 as will be understood and the signal switch thus serving in exactly the same capacity as switch 71.

The upper contact leaf 128 has an extension 136 cooperating with the cam 79 to control the duration of the signals as has been described.

The lug 132 is secured to the disk 133 by a screw 137 and the disk has several other openings 138 to receive similar screws for mounting other lugs (not shown) by means of which signals may be given in groups at one minute, or two and one-half minute intervals. In other words, the circuit switch 42 being held closed for a full five minute period, the lugs on the disk 133 will complete the circuit to the signal either once during the five minute period, as here shown, or twice or five times in the same length of time, by proper mounting of the lugs.

Attention is called to the dial 139 carried by the shaft 140 on which the disk 133 is mounted. At one point, corresponding to the position in which the lug 132 closes the signal switch 42, this dial carries on its forward side the word "Set" which will be visible through an opening 141 in the panel 15. The program chain is set up initially only when this word "Set" is in view in order that the circuit switch closing will be properly synchronized with that of the signal switch as will be understood.

The driving sprocket 25 in each type of clock may have imprinted thereon, or secured thereto as herein shown, an indicating pointer 142 to facilitate proper location of the sprockets on the minute hand spindle.

Aside from the foregoing differences in the control over the program of signals by this signal switch 42 the clock shown in Figures 6 and 7 operates exactly the same as that previously described and will not, therefore, be set out in detail.

Having now fully described my invention, what I claim as new and desire to secure by Letters Patent is:

1. In an electric program clock of the kind referred to, a vertically elongated housing including frontal and rear housing members hingedly connected at one side to open laterally apart and to close together at their meeting margins, the two housing members being separated interiorly by means of an instrument panel mounted over the frontal side of the rear housing member, an electric clock unit mounted upwardly upon the inner side of the instrument panel and having its hour hand spindle, minute hand spindle and second hand shaft extended through the panel to the front thereof, a timing dial on the front of the panel and centered upon the said shafts which pass through the dial, a sweep second hand at the outer end of the second hand shaft, a pair of driving sprockets on the minute hand spindle inwardly of the second hand, linked program chains trained over said sprockets and depended into the base of the housing, a tubular shield in the housing for enclosing the depended ends of the chains, circuit control switches for the said drive sprockets, signal clips mounted in suitably spaced relation on the program chains and arranged to co-operate with the circuit control switches in measuring off time periods, and a source of electrical energy and suitable wiring and connections for operating the clock.

2. In a program clock assembly according to claim 1, a calendar switch mechanism for stopping the clock for pre-selected time periods.

3. In a program clock assembly according to claim 1, the sprocket rotated by the minute hand spindle of the clock unit being arranged to advance one tooth per minute, a signal controlling switch device adjacent the chain and arranged to be actuated by the said signal clips of the chain.

10 LEON V. LASSITER.
